SAMUEL ROEBUCK AND JOHN ROEBUCK, OF NEW YORK, N. Y.

Design No. 3,252, dated November 17, 1868.

DESIGN FOR A CUSPADORE.

The Schedule referred to in these Letters Patent and making part of the same.

To all whom it may concern:

Be it known that we, SAMUEL ROEBUCK and JOHN ROEBUCK, of the city, county, and State of New York, have originated and designed a new Pattern for Cuspadores, or Cospitores, of which the following is a full, clear, and exact description, reference being had to the accompanying photograph, making part of this specification.

The photograph represents a hollow vessel, A, manufactured in earthen material, having a series of flattened surfaces, B B, forming a part of its outward configuration, and intended to receive ornamental impressions or designs in color, gold-leaf, or other suitable material, the said vessel being intended to be used as a receptacle for waste matter in parlors, &c., or as a spittoon.

Similar vessels are already made by ourselves and others, all of which are formed on one general model,

having plain rounded surfaces, differing from each other only in height, diameter, or outline.

The vessel A produced by us is the first, intended for the same uses, in which a variation from a plain rounded surface has been introduced as a part of the ornamental effect. Its advantages are, novelty of form, and great adaptability for the reception of certain kinds of ornamentation.

Having thus described the vessel,

What we claim as new, and our invention, and desire to secure by Letters Patent, is—

The design for a cuspadore or cospitore, as herein represented and set forth.

SAMUEL ROEBUCK. [L. S.]
JOHN ROEBUCK. [L. S.]
